(57) **ABSTRACT**

A hair entrapment device for retaining loose hair entering a drainage well of a drain, the device comprising: an annular sleeve body having an upper open end and a lower open end respectively defining a top opening and a bottom opening; and a sidewall extending between the upper open end and the lower open end; a central hub; spokes extending between the central hub and portions of an inner surface of the sidewall, and defining spoke openings between the central hub, the spokes and the inner surface; a plurality of tines extending from the spokes towards the top opening; and wherein fluid flows via the top opening, the spoke openings and the bottom opening into the drain and loose hair is retained by the plurality of tines.

HAIR ENTRAPMENT FILTER SYSTEM

FIELD

Aspects of this disclosure relate to hair straining devices. 5

BACKGROUND

Clogged drains or traps associated with bathtubs, sinks and shower stalls are a common household problem, and they can be unsightly, inconvenient, and may result in unpleasant odors. The primary cause for most clogs of traps and drains is the accumulation of loose human hair or pet hair strands shed from hair washing and shampooing, combing, or bathing. The blockages may be removed using a variety of chemical means such drain cleaners, including liquids, gels, powders, and mechanical means such as plungers, hand augers or drain snakes.

SUMMARY

In one example, there is provided a hair entrapment device for retaining loose hair entering a drainage well of a drain, the device comprising:

an annular sleeve body having an upper open end and a lower open end respectively defining a top opening and a bottom opening, and a sidewall extending between the upper open end and the lower open end; a central hub; spokes extending between the central hub and portions of an inner surface of the sidewall, and defining spoke openings between the central hub, the spokes and the inner surface of the sidewall; a plurality of tines extending from the spokes towards the top opening; and

wherein fluid flows via the top opening, the spoke openings and the bottom opening into the drain and the loose hair is retained by the plurality of tines.

In another example, there is provided a hair entrapment device comprising:

a central hub having a top end and a bottom end; a plurality of spokes extending from the central hub and defining openings between the spokes, each of the plurality of spokes opposed sidewalls, a top wall and a bottom wall;

a plurality of tines extending from the top wall; and wherein fluid flows via the openings and loose hair is retained by the plurality of tines.

In another example, there is provided a kit comprising: a hair entrapment device comprising an annular sleeve body having an upper open end and a lower open end respectively defining a top opening and a bottom opening; and a sidewall extending between the upper open end and the lower open end; a central hub; spokes extending between the central hub and portions of an inner surface of the sidewall, and defining spoke openings between the central hub, the spokes and the inner surface; a plurality of tines extending from the spokes towards the top opening; and

a tool comprising a tool body with complementary fingers are snugly received by the spoke openings and engage the inner surface.

In another example, there is provided a method of trapping loose hair entering a drainage well of a drain, the method comprising:

introducing a hair entrapment device into the drainage well; the hair entrapment device comprising an annular

sleeve body having an upper open end and a lower open end respectively defining a top opening and a bottom opening; and a sidewall extending between the upper open end and the lower open end; a central hub; spokes extending between the central hub and portions of an inner surface of the sidewall, and defining spoke openings between the central hub, the spokes and the inner surface; a plurality of tines extending from the spokes towards the top opening; applying a force on the hair entrapment device to cause an outer surface of the sidewall to engage a drain wall of the drain; and whereby fluid flows via the openings into the drain and loose hair is retained by the plurality of tines.

Advantageously, the hair entrapment device reduces or eliminates the use of drain-cleaning chemicals that may be harmful to the environment and/or toxic to breathe or harmful when in contact with the skin or eyes. In addition, the device is easy to use, re-usable, environmentally friendly and relatively inexpensive compared to other tools or chemical means.

BRIEF DESCRIPTION OF THE DRAWINGS

FIG. 1a shows a top perspective view of a hair entrapment device, in one embodiment;

FIG. 1b shows a perspective view of a drain;

FIG. 10b shows a front elevational view of the hair entrapment device of FIG. 10a;

FIG. 10c shows a top view of the hair entrapment device of FIG. 10a;

FIG. 10d shows a bottom view of the hair entrapment device of FIG. 10a;

FIG. 11a shows a top perspective view of a hair entrapment device, in another embodiment;

FIG. 11b shows a front elevational view of the hair entrapment device of FIG. 11a;

FIG. 11c shows a top view of the hair entrapment device of FIG. 11a;

FIG. 11d shows a bottom view of the hair entrapment device of FIG. 11a; and

FIG. 12 shows a top view of a hair entrapment device, in yet another embodiment.

DETAILED DESCRIPTION

FIG. 1a shows hair entrapment device 10 comprising annular sleeve body 12 having upper open end 14 and lower open end 16 respectively defining a top opening 18 and bottom opening 20; and sidewall 22 extending between upper open end 14 and lower open end 16, comprising inner sleeve wall surface 24 and outer sleeve wall surface 26. Located in the middle of top opening 18 and bottom opening 20 of annular sleeve body 12 is central hub 30 maintained centrally within annular sleeve body 12 by a plurality of spokes 32 which extend from central hub wall 34 of central hub 30 to inner sleeve wall surface 24 of the sidewall 22. Spokes 32 comprise a plurality of tines 40 extending towards top opening 18, and spoke openings 42 are defined between spokes 32, central hub wall 34 and inner sleeve wall surface 24. As shown in FIG. 1b, hair entrapment device 10 may be inserted in drainage well 44 of drain 46 associated with a bathtub, a shower stall, a sink, or any other type of drain of any size. After hair entrapment device 10 is installed in drainage well 44, a water tap associated with the bathtub, the shower stall or the sink is turned on during a cleansing event, such as bathing, a showering or hair washing event. Following, or during, the cleansing event, the water discharged from the bathtub, the shower stall or the sink, flows via top opening 18, spoke openings 42 and bottom opening 20 into drain 46 and any loose hair being carried by the fluid is captured by the plurality of tines 40.

As shown in FIG. 1c, each spoke 32 comprises upstanding wall 50 with tines 40, which may be integrally-formed. Each of tines 40 are separated from other tines 40 by spacing 51 dimensioned to accommodate strands of hair, such human hair or pet hair. The diameter of human hair is generally known to range between 17 μm to 181 μm . In addition, the surrounding wall surface of tines 40 may be rough to enhance the capture of the hair. Sidewall 22 comprises a plurality of crevices 52 formed therethrough and extending

for a predefined distance from the upper open end 14. Crevices 52 allow annular sleeve body 12 to be flexible and facilitate the installation of hair entrapment device 10 in drainage well 44 of drain 46. Accordingly, hair entrapment device 10 may be installed in differently sized drains 46. Crevices 52 may comprise different dimensions, which may impact the level of flexibility of annular sleeve body 12.

Looking at FIGS. 1d-1g, central hub 30 comprises knob 60, neck 62 and belly 64. In one example, knob 60 and neck 62 are positioned above top opening 18. Knob 60 may be grasped by a hand or a tool when installing in drain 46 or extricating from drain 46. In one example, belly 64 comprises hollow portion 66. FIG. 1h shows a plurality of hair entrapment devices 10 stacked on top of each other, in which knob 60, neck 62 of one device 10 is received by hollow portion 66 of another hair entrapment device 10. Accordingly, hollow portion 66 facilitates stacking of hair entrapment device 10 for packaging, transportation, or storage when not in use.

In operation, a downward force is applied on hair entrapment device 10 to urge hair entrapment device 10 downwardly into drainage well 44 such that outer sleeve wall surface 26 of annular sleeve body 12 is in tight, sealing engagement with the drain wall 68 of drainage well 44. In one example, the force is applied to knob 60 and/or spokes 32. Fluid flows via top opening 18, spoke openings 42 and bottom opening 20 and loose hair is captured by the plurality of tines 40. Spokes 32 and spoke openings 42 are dimensioned such that the flow of water around spokes 32 into drainage well 44 is not substantially limited, and therefore flows at an acceptable rate that is substantially similar to the rate of flow without hair entrapment device 10 installed within drainage well 44. Accordingly, there is no substantial difference in the flow rate with or without hair entrapment device 10 installed within drainage well 44. In one example, hair entrapment device 10 is urged into drainage well 44 until bottom portion of sidewall 22 and bottom portions of spokes 32 are adjacent to, or abut, cross members 69 of drain 46.

In one implementation, sidewall 22 is substantially frustoconical, and tapering from upper open end 14 and lower open end 16. Frustoconical sidewall 22 aids in securement of hair entrapment device 10 within drainage well 44. Accordingly, hair entrapment device 10 is able to fit into a plurality of differently sized drains 46. For example, a portion of the tapered lower end of annular sleeve body 12 may be received within drainage well 44 while the upper portion of annular sleeve body 12 is free of drainage well 44.

As noted above, knob 60 may be grasped by a tool when installing in drainage well 44 or extricating hair entrapment device 10 from drainage well 44. FIGS. 2a-2e show various views of exemplary tool 70 which comprises unitary body 72 dimensioned to be received by hair entrapment device 10 via upper open end 14. Unitary body 72 comprises top end 74 with top wall 75, and bottom end 76 with bottom wall 78, and surrounding wall 80. Central aperture 81 extends between top wall 75 and bottom wall 78, and a plurality of fingers 82 formed from top wall 75 and bottom wall 78, with fingers 82 separated from each other by cut-outs 84 which extend from surrounding wall 80 to aperture wall 85 defining central aperture 81. As such, the shape and dimensions of the plurality of fingers 82 is complementary to the shape and dimensions of spoke openings 42, while the shape and dimensions of cut-outs 84 correspond to the shape and dimensions of spokes 32. Top wall 75 also includes handle 88 for facilitating the handling of tool 70 when installing

hair entrapment device 10 in drainage well 44 or extricating hair entrapment device 10 from drainage well 46.

The operation of hair entrapment device 10 and tool 70 will now be described. In one example, before a cleansing event, such as taking a shower or washing one's hair or other hair shedding event, hair entrapment device 10 is installed in drainage well 44 associated with drain 46. When installed, outer sleeve wall surface 26 of hair entrapment device 10 is in tight, sealing engagement with the drain wall 68 of drainage well 44 with the water. During, or after, the hair shedding event loose hair that would normally flow into drainage well 44 is captured by the plurality of tines 40 of hair entrapment device 10. More specifically, a shed hair strand is carried by the flowing water towards drain 46, and as the hair strand advances into drainage well 44 a portion of the hair strand enters one or more spacings 51 of tines 40 associated with one or more of spokes 32. As the water continues to flow into drainage well 44 other portions of the hair strand also enter one or more spacings 51 of tines 40 associated with one or more of spokes 32. As the water continues to flow the process repeats itself and a sufficient portion of the hair strand is retained within spacings 51 of tines 40 such that the strand of hair is thereby prevented from going down drain 46, and the hair strand accumulates within hair entrapment device 10. Furthermore, any swirling action of the water as it enters drainage well 46 further enhances the capture of the hair strand by tines 40.

Following the hair shedding event, the accumulated, tangled loose hair may need to be removed from hair entrapment device 10 to permit re-use, alternatively, a clean or new device 10 may be used instead. Preferably, hair entrapment device 10 is extricated from drainage well 44 first. While this may be performed by inserting one's hand into drainage well 44 to grab hair entrapment device 10 by knob 60 and applying an upward force, a tool may be used, such as tool 70. Accordingly, tool 70 may be introduced into the mouth of drainage well 44, and with central aperture 81 aligned with central hub 30, cut-outs 84 aligned with spokes 32, and the plurality of fingers 82 aligned with spoke openings 42, a downward force is applied to handle 88. As the force is applied, knob 60 and neck 62 of central hub 30 are forced through aperture 86, and spokes 32 are received by cut-outs 84, and the plurality of fingers 82 are received by spoke openings 42, and belly 64 abuts aperture wall 85 of the plurality of fingers 82. Tool 70 is caused to travel down along inner sleeve wall surface 24 of sidewall 22 until bottom wall 78 of the plurality of fingers 82 is adjacent to lower open end 16, or at least until the top edge of tines 40 is adjacent to the top section of cut-outs 84, while taking into account the captured hair strands which is trapped therewith, thereby placing tool 70 in a deployed position. From the deployed position, the combination of hair entrapment device 10 and tool 70 may be removed from drainage well 44 by pinching knob 60 and applying a lifting force to cause outer sleeve wall surface 26 of annular sleeve body 12 to slide upwardly along drain wall 68 until the combination of hair entrapment device 10 and tool 70 are out of drainage well 44, along with the trapped hair.

In one implementation, hair entrapment device 90 as shown in FIGS. 3a-3d comprises annular sleeve body 12, and sidewall 22 comprising inner sleeve wall surface 24 and outer sleeve wall surface 26. Hair entrapment device 90 is similar to hair entrapment device 10, however, sidewall 22 of hair entrapment device 90 comprises a plurality of upstanding posts 91 extending from upper open end 14. Looking at FIG. 4, there is shown hair entrapment device 90 that has been removed from drainage well 44 following a

cleansing event in which hair 92 was shed. Loose hair 92 otherwise destined to flow down drain 46 associated with bathtub 93 and potentially result in a blockage of drain 46 is seen to have been snagged by tines 40 of hair entrapment device 90. Also, the plurality of upstanding posts 91 also snag loose hair 92, especially as water swirls down drain 46. The swirling effect caused by the water causes loose hair 92 to swirl too, and in doing so loose hair 92 wraps around posts 91 and/or tines 40, as shown in FIG. 4. Hair entrapment device 90 may be removed from drainage well 46 and the accumulated tangled loose hair 92 is removed therefrom, thereby permitting re-use of hair entrapment device 90. Alternatively, hair entrapment device 90 with the accumulated hair may be disposed of.

FIG. 5 shows tool 94 installed within hair entrapment device 90 for facilitating installation of hair entrapment device 90 in drainage well 44 or extrication of hair entrapment device 10 from drainage well 44. Tool 94 is similar to tool 70, and comprises unitary body 72 dimensioned to be received by hair entrapment device 90 via upper open end 14, with surrounding wall 80. A plurality of fingers 82 are formed from adjacent top wall 75 and bottom wall 78 and fingers 82 are separated from each other by primary cut-outs 84, with central aperture 81 extending between top wall 75 and bottom wall 78. Accordingly, primary cut-outs 84 extend from surrounding wall 80 to aperture wall 85 defining central aperture 81. As such, the shape and dimension of the plurality of fingers 82 is complementary to the shape and dimension of spokes 32 and spoke openings 42. Top wall 75 also includes handle 88 for facilitating installing in drain 46 or extricating hair entrapment device 10 from drainage well 44. Secondary cut-outs 95 extend from top wall 75 to bottom wall, and secondary cut-outs 95 are dimensioned to receive upstanding posts 91 when tool 94 is installed within hair entrapment device 90, as shown in FIG. 5.

In one implementation, there is shown in FIGS. 6a and 6b hair entrapment device 100, which is similar to hair entrapment device 10 and comprises like elements. Hair entrapment device 100 comprises annular sleeve body 112 having upper open end 114 and lower open end 116 respectively defining top opening 118 and bottom opening 120. Sidewall 122 comprises inner wall surface 124 and outer wall surface 126, extends between upper open end 114 and lower open end 116. Located in the middle of top opening 118 and bottom opening 120 of annular sleeve body 112 is central hub 130 maintained centrally within annular sleeve body 112 by a plurality of spokes 132 extending from central hub wall 134 of central hub 130 to inner wall surface 124 of the sidewall 122. Spokes 132 comprise a plurality of integrally formed tines 140 extending towards top opening 118, and spoke openings 142 are defined between spokes 132, central hub wall 134 and inner wall surface 124. Sidewall 122 comprises a plurality of upstanding posts 150 extending from upper open end 114. Sidewall 122 also comprises a plurality of crevices 152 formed therethrough and extending for a predefined distance from the upper open end 114. Crevices 152 allow annular sleeve body 112 to be flexible and facilitate the installation of hair entrapment device 100 in drainage well 44 of drain 46.

Once installed within drainage well 44, tines 140 of hair entrapment device 100 snag loose hair 92 carried by water during or after a hair shedding event, that is, loose hair 92 that would otherwise flow down drain 46 and potential result in a blockage of drain 46. The plurality of upstanding posts 150 also snag loose hair 92, especially as water swirls down drain 46. The swirling effect caused by the water causes loose hair 92 to swirl too, and in doing so loose hair 92

wraps around posts 150 and/or tines 140. Following the hair shedding event, tangled loose hair 92 is removed from hair entrapment device 100.

As shown in FIGS. 6a and 6b, central hub 130 comprises knob 160, neck 162 and belly 164. Knob 160 may be grasped by a hand or tool 170 when installing hair entrapment device 100 in drain 46 or extricating from drain 46. Tool 170 is similar to tool 70 and comprises like elements. Accordingly, tool 170 comprises unitary body 172 dimensioned to be received by hair entrapment device 10 via upper open end 114. Unitary body 172 comprises top end 174 with top wall 175, and bottom end 176 with bottom wall 178, and surrounding wall 180. A plurality of fingers 182 are formed from adjacent top wall 175 and bottom wall 178 and fingers 182 separated from each other by primary cut-outs 184 extending from surrounding wall 180 to aperture wall 185 defining central aperture 186. As such, the shape and dimension of the plurality of fingers 182 is complementary to the shape and dimension of spokes 140 and spoke openings 142. Similarly, primary cut-outs 184 are dimensioned to receive spokes 132. Top wall 175 also includes handle 188 for facilitating installing in drain 46 or extricating hair entrapment device 10 from drain 46. Secondary cut-outs 190 extend from top wall 175 to bottom wall 178, and secondary cut-outs 190 are dimensioned to receive upstanding posts 150 when tool 170 is installed within hair entrapment device 100.

In one implementation, there is shown hair entrapment device 192, similar to hair entrapment device 10 and having like elements, comprising spokes 194 with tines 196, and upstanding posts 198, in FIGS. 6c and 6d.

FIG. 7 shows an exploded view of hair entrapment device 100, tool 170 and drain 46, and illustrates the alignment of the particular elements of hair entrapment device 100, tool 170 and drain 46 for installation of hair entrapment device 100 within drainage well 44 or removal of hair entrapment device 100 from drainage well 44.

In one implementation, there is shown hair entrapment device 200, similar to hair entrapment device 10 and having like elements, comprising eight spokes 202 with tines 204, and upstanding posts 206, in FIGS. 8a-8d.

In one implementation, there is shown tool 210, similar to tool 70 and having like elements, comprising eight fingers 212, eight primary cut-outs 214 for receiving tines 204 of hair entrapment device 200 and eight secondary cut-outs 216 for receiving upstanding posts 206, in FIGS. 9a-9c.

In one implementation, there is shown hair entrapment device 300, similar to hair entrapment device 10 and having like elements, comprising eight spokes 302 with tines 304, in FIGS. 10a-10d.

In one implementation, there is shown hair entrapment device 400 similar to hair entrapment device 10 and having like elements, in FIGS. 11a-11d. Sidewall 22 of hair entrapment device 400 comprises flange 402 extending from outer sleeve wall surface 26. For example, flange 402 may extend from outer sleeve wall surface 26 adjacent to upper open end 14. Flange 402 may facilitate installation of hair entrapment device 400 in differently-sized drainage wells 44.

In one implementation, there is shown hair entrapment device 500 comprising central hub 502, a plurality of spokes 504 extending from central hub 502, in FIG. 12. Each of the plurality of spokes 504 comprises opposed side walls 506, 508, top wall 510 with a plurality of tines 512, bottom wall 514 and distal wall 516. Hair entrapment device 500 is installed in drainage well 44 as described above such that distal wall 516 abuts inner surface wall of drainage well 44. Accordingly, in use, water flows between openings defined

spokes 504 and drain wall 68 of drainage well 44, and loose hair is held between the plurality of tines 512.

In one implementation, unitary body 72 of tool 70 is substantially frustoconical, and tapering from top end 74 and bottom end 76; and unitary body 172 of tool 170 is substantially frustoconical, tapering from top end 174 and bottom end 176.

In one implementation, hair entrapment devices 10, 90, 100, 192, 200, 210, 300, 400, 500 are made of any suitable material.

In one implementation, hair entrapment devices 10, 90, 100, 192, 200, 210, 300, 400, 500 are made of a flexible, suitable resilient plastic or elastomeric material. Exemplary materials comprise any of a stiff synthetic rubber material, a polyolefin, a polyvinylchloride, a polyamine resin, or the like.

In one implementation, hair entrapment devices 10, 90, 100, 192, 200, 300, 400 and tools 70, 170, 210 are biodegradable. In one example, hair entrapment devices 10, 90, 100, 192, 200, 210, 300, 400, 500 are made of polylactic acid (PLA).

In one implementation, hair entrapment devices 10, 90, 100, 192, 200, 210, 300, 400, 500 are made of any of a metal and a metal chrome.

In one implementation, a combination of hair entrapment device 10, 90, 100, 192, 200, 300, 400, 500 and tool 70, 170, 210 acts a drainage well stopper or plug.

In one implementation, tines 40a-g may comprise varying dimensions, with tines 40a closest to central hub wall 34 being substantially longer than tines 40g adjacent to inner sleeve wall surface 24.

In one implementation, tines 40a-g comprise identical dimensions.

In one implementation, tines 40a-g comprise varying dimensions. In one example, tines 40a-g comprise different lengths, different widths, different breadths.

In one implementation, tines 40a-g may be positioned in any configuration. For example, tines 40a-g may comprise alternating heights, or tines 40a closest to central hub wall 34 and tines 40g adjacent to inner sleeve wall surface 24 may be substantially longer than tines 40b-f, or versa.

In one implementation, tines 40 are formed on a separate body that is removably attached to spokes 32. Accordingly, once hair has accumulated on tines 40, the body may be removed from spokes 32 and the body with the accumulated hair is disposed of. Accordingly, the removably attached tines 40 may be a disposable accessory, should the user choose not to remove the accumulated hair for re-use of tines 40.

The benefits and advantages described above may relate to one embodiment or may relate to several embodiments. The embodiments are not limited to those that solve any or all of the stated problems or those that have any or all of the stated benefits and advantages. The operations of the methods described herein may be carried out in any suitable order, or simultaneously where appropriate. Additionally, individual blocks may be added or deleted from any of the methods without departing from the spirit and scope of the subject matter described herein. Aspects of any of the examples described above may be combined with aspects of any of the other examples described to form further examples without losing the effect sought.

Benefits, other advantages, and solutions to problems have been described above with regard to specific embodiments. However, the benefits, advantages, solutions to problems, and any element(s) that may cause any benefit, advantage, or solution to occur or become more pronounced are

not to be construed as critical, required, or essential features or elements of any or all the claims. As used herein, the terms "comprises," "comprising," or any other variations thereof, are intended to cover a non-exclusive inclusion, such that a process, method, article, or apparatus that comprises a list of elements does not include only those elements but may include other elements not expressly listed or inherent to such process, method, article, or apparatus. Further, no element described herein is required for the practice of the invention unless expressly described as "essential" or "critical."

The preceding detailed description of exemplary embodiments of the invention makes reference to the accompanying drawings, which show the exemplary embodiment by way of illustration. While these exemplary embodiments are described in sufficient detail to enable those skilled in the art to practice the invention, it should be understood that other embodiments may be realized and that logical and mechanical changes may be made without departing from the spirit and scope of the invention. For example, the steps recited in any of the method or process claims may be executed in any order and are not limited to the order presented. Thus, the preceding detailed description is presented for purposes of illustration only and not of limitation, and the scope of the invention is defined by the preceding description, and with respect to the attached claims.

The invention claimed is:

1. A hair entrapment device for retaining loose hair entering a drainage well of a drain, the device comprising: an annular sleeve body having an upper open end and a lower open end respectively defining a top opening and a bottom opening, the annular sleeve body comprising a sidewall extending between the upper open end and the lower open end; a central hub; a plurality of planar spokes radially extending between the central hub and portions of an inner surface of the sidewall, defining spoke openings between the central hub, the spokes and the inner surface; and a plurality of tines extending from a top surface of the spokes towards the top opening, each of the plurality of tines being spaced a parallel distance from each other, defining channels substantially uniform in width theretwix, wide enough to receive strands of hair therein; wherein fluid flows the through the top opening, through the spoke openings and through the bottom opening into the drain and any loose hair flowing therewith, is

retained in the channels substantially uniform in width between the plurality of tines.

2. The hair entrapment device of claim 1, wherein the sidewall is substantially frustoconical and tapered inwardly from the upper open end to the lower open end.
3. The hair entrapment device of claim 1, wherein the annular sleeve body is detachably engageable with a wall of the drainage well.
4. The hair entrapment device of claim 1, wherein the annular sleeve body comprises a resilient material.
5. The hair entrapment device of claim 1, wherein the sidewall comprises a plurality of crevices formed therethrough and extending for a predefined length from the upper open end.
6. The hair entrapment device of claim 1, wherein at least some of the plurality of tines extend different distances.
7. The hair entrapment device of claim 1, wherein the plurality of planar spokes are substantially triangular in shape.
8. The hair entrapment device of claim 1, wherein the sidewall comprises upstanding posts extending beyond the upper open end.
9. The hair entrapment device of claim 1, wherein the hub further comprises a knob for grasping.
10. The hair entrapment device of claim 1, wherein the sidewall further comprises a flange.
11. The hair entrapment device of claim 1, wherein the device is constructed and arranged such that a plurality of hair entrapment devices are capable of being stacked on top of each other in a nested manner.
12. The hair entrapment device of claim 1, wherein at least some components of the device are made from a synthetic rubber.
13. The hair entrapment device of claim 1, wherein at least some components of the device are made from polylactic acid.
14. The hair entrapment device of claim 1, wherein at least some components of the device are made from a metal.
15. The hair entrapment device of claim 1, wherein at least some components of the device are made from a polyolefin.
16. The hair entrapment device of claim 1, wherein at least some components of the device are made from a polyvinylchloride.
17. The hair entrapment device of claim 1, wherein at least some components of the device are made from a polyamine resin.
